UNITED STATES PATENT OFFICE.

CHRISTOPHER HYMERS, OF ST. LOUIS, MISSOURI.

COMBINED FURNITURE LEG AND CASTER.

No. 880,997.

Specification of Letters Patent.

Patented March 3, 1908.

Application filed May 16, 1907. Serial No. 374,028.

To all whom it may concern:

Be it known that I, CHRISTOPHER HYMERS, a citizen of the United States of America, residing at the city of St. Louis, in the State of Missouri, have invented certain new and useful Improvements in Combined Furniture Legs and Casters, of which the following is a full, clear, and exact description, reference being had to the accompanying drawing, forming part of this specification.

My invention relates to a combined leg and caster for articles of furniture and it has for its object to provide a device of this character whereby the articles of furniture, when supplied with a desired number of the legs and casters, may be susceptible of remaining in a stationary or fixed lowered position without the liability of becoming shifted and also susceptible of being readily elevated and moved upon a floor without the necessity of lifting it.

It is highly desirable in many articles of furniture that they be so mounted as not to be readily shifted when pressure is exerted against them and therefore it is important that such articles be provided with legs which ordinarily rest upon the floor after they are located in position for use and consequently, casters that rest constantly upon the floor in connection with the legs of the articles of furniture are unsatisfactory for the reason that they permit of the article being readily shifted. By my improvement the article of furniture supplied with it may ordinarily rest steadily and not be readily shiftable when in use but when the article of furniture is to be moved upon the floor, such movement may be readily accomplished by throwing the caster forming a part of the improvement from a position of non-serviceability to a position of serviceability, whereby the body of the furniture leg which previously rested upon the floor is elevated from the floor to remain elevated during the period that the caster is in service.

Figure I is a vertical section taken through my combined leg and caster. Fig. II is a rear elevation of the leg and caster. Fig. III is a similar view to Fig. I with the leg shown in elevated position and illustrating a modified form of caster roller.

In the accompanying drawings: 1 designates the leg of a piece of furniture, such as a stove, and which is provided at a point, preferably near its lower end, with a horizontally disposed bearing member 2 containing a ver-

tical perforation 3. At the upper end of the leg is a vertical depending guide stem 4.

5 designates a caster sleeve or hollow stem slidably fitted in the aperture of the bearing member 2 and loosely surrounding the depending guide stem 4 in order that it may be moved vertically relative to the leg 1. This caster sleeve is provided with a vertical slot 6. 7 is a carrier having a shank that is loosely seated in the lower end of the sleeve 5 to which it is pivotally connected by a pin that passes vertically through the carrier and is seated in the sleeve as seen in Fig. I. 9 is a caster roller mounted in the carrier 7.

10 designates a cam lever mounted in the vertical slot of the sleeve 5 and pivotally connected thereto by a pivot pin 11 that passes horizontally through the sleeve and lever at a point beneath the guide stem 4. The cam lever is provided at its rear edge with a seat 12, preferably concaved, which is adapted to impinge against the lower end of the depending guide stem 4 when the cam lever is moved to carry said rear edge of the cam lever to the guide stem.

The caster roller 9 may be of the wheel type illustrated in Figs. I and II or of the ball type illustrated in Fig. III, and the carrier 7 in which the roller is mounted may be of a construction that is suitable for either type of roller. When, in the practical use of my combined furniture leg and caster, the leg is at rest upon a floor as illustrated in Figs. I and II, the various parts of the caster are in the elevated positions seen in the figures mentioned so that the caster roller will rest idly upon the floor and out of service. To put the caster into position for service as a support for the leg and the article of furniture, the handle of the cam lever 10 is grasped and moved downwardly from the position seen in Figs. I and II to the position seen in Fig. III, whereby the cam of the cam lever by bearing against the lower end of the depending guide stem 4 above it is caused to exert a lifting action upon said depending guide stem within the sleeve 5 while the roller of the caster is resting firmly upon the floor which offers resistance to the downward movement of said roller and necessitates upward movement of the depending guide stem within the sleeve 5 and the article of furniture with the result of elevating the leg that is a companion to the caster from the floor as will be readily understood.

As the cam lever is moved the seat 12 at its rear

edge is carried to the lower end of the depending guide stem 4 and, due to the impingement of the depending guide stem against said seat, the cam lever is held from movement with the result of locking the caster from movement relative to the leg 1, whereby the leg is caused to be sustained by the caster until the cam lever is again moved and its seat portion is moved away from the depending guide stem, and the caster is thrown out of operation while the leg of the piece of furniture with which the caster is associated is lowered to the floor as before. While I have shown the leg with which my caster is associated as one having the form common to those used for supports of stoves, it is obvious that the leg may be of any other desired form or shape suitable for use with any article of furniture other than the stove,

such for instance, as a refrigerator, a piano, 20
store counter or bedstead.

I claim:

The combination of a leg having a depending guide stem and a horizontally disposed bearing member formed with a vertical perforation beneath the depending guide stem, 25
a slideable caster sleeve formed with a vertical slot and receiving the depending guide stem and extending downwardly through the vertical perforation, a pivot pin extending through the caster sleeve across the vertical slot, and a cam lever having a cam mounted on the pivot pin within the vertical slot beneath the depending guide pin. 30

CHRISTOPHER HYMERS.
